Primary Examiner—Celia Murphy**Attorney, Agent, or Firm**—Sterne, Kessler, Goldstein & Fox, P.L.L.C.**[57]****CLAIM**

The ornamental design for a repeat pattern of a shoe sole, as shown and described.

DESCRIPTION

FIG. 1 is a top plan view of a repeat pattern of a shoe sole showing my new design, the broken lines shown along the borders representing the boundaries of the repeat units, and not being claimed as part of the design; and,

FIG. 2 is an enlarged fragmentary view taken on line 2—2 of FIG. 1.
